UNITED STATES PATENT OFFICE.

CHARLES WRAY, OF CROYDON, ENGLAND, ASSIGNOR TO HIMSELF AND CONQUEST
JOHN STANLEY, OF LONDON, ENGLAND.

GAS FIRE, ELECTRIC RADIATOR, AND THE LIKE.

1,398,663.

Specification of Letters Patent. Patented Nov. 29, 1921.

Application filed February 6, 1920. Serial No. 356,769.

To all whom it may concern:

Be it known that I, CHARLES WRAY, a subject of the King of Great Britain and Ireland, and resident of Croydon, in the county of Surrey, England, have invented new and useful Improvements in or in connection with Gas Fires, Electric Radiators, and the like, (for which I have filed application in Great Britain Oct. 10, 1918, Patent No. 119,604,) of which the following is a specification.

This invention relates to gas fires, electric radiators and like heating apparatus, and it has for its object to provide means by which the radiant heat from the gas fires or radiator shall be reflected more efficiently into the room or compartment than is the case with heating apparatus as at present constructed. The invention also has for its object to provide means by which the deleterious effect of currents of cold air passing across the face of or in relation to the fire from the sides and bottom of the stove shall be prevented.

25 In a gas fire, electric radiator or like heating apparatus there is combined, in accordance with this invention, with a heat reflector consisting of, for example, a polished sheet of metal, disposed at the lower portion 30 of the heating apparatus and extending outward from the front thereof, for example, substantially horizontal, two upwardly extending plates, for example, of polished metal, extending forwardly from the heating 35 apparatus one on each side thereof, for the purpose of reflecting the heat upward and outward into the room, and of preventing or excluding currents of cold air passing across the face of the fire from below and 40 from the sides.

A heat reflector and draft excluder according to the present invention and applied to a gas stove will now be described with reference to the accompanying drawing.

45 The heat reflector comprises a plate 1 of polished metal supported at the rear end 2 on the front of the gas stove 3 itself. In some constructions the plate may extend below the stove so as to close the bottom thereof 50 to the flow of cold air in relation to or between the heating elements of the stove. At each side two upwardly extending plates of polished metal 4 are secured to the horizontal reflector 1 by the screws 5. The plates are

made of a height to achieve the purpose 55 mentioned.

To the sides of the upwardly extending plates are fixed screws 6 which pass through slots 7 in the bars 8. The bars 8 constitute legs which are secured by the fly-nuts 9. 60 With this construction the legs may be adjusted in height as desired.

The metal plates 1 and 4 are highly polished and reflect the heat, which is distributed downwardly and sidewise by the 65 fire, and upward and outward into the room. The upwardly extending plates 4 also act to exclude drafts from the front of the fire.

The reflector and draft excluder according to the present invention may conveniently 70 be made of brass, copper or nickel, which is highly polished, and the upwardly extending plates 4 may, if desired, be formed in one piece with the horizontal plate 1. Further, the upwardly extending plates may be adjustable in position on the horizontal plate 75 1, for example, so that their angles with the front of the stove may be fixed as is found convenient.

In certain cases it may be convenient to 80 arrange the two upwardly extending plates 4 at a small distance above the horizontal plate 1.

Though the heat reflector has been described with legs at the two front corners, 85 it is to be understood that instead of supporting the rear end on the heating apparatus it may also be provided with legs which, if desired, can be adjustable in height; and the reflector may be fixedly 90 attached to the heating apparatus.

What I claim is:—

1. A portable heat reflector and draft excluder, comprising a substantially horizontally disposed heat reflecting plate, opposite 95 side substantially vertically disposed plates supported on and movable with said horizontally disposed plate, and supporting and adjusting means for the forward end of said plates, the said plates at the rear end portion adapted to be detachably supported by and extend forwardly from a heating apparatus. 100

2. In combination with heating apparatus, 105 a heat reflector and draft excluder, comprising a substantially horizontally disposed plate extending forwardly from the heating apparatus, a pair of spaced substantially ver-

tically disposed plates at opposite sides of said horizontally disposed plate and extending upwardly therefrom, and supports mounted on said side plates for supporting the outer end of the heat reflector and draft excluder, for the purposes substantially as described.

3. In a heat reflector and draft excluder, the combination of a horizontally disposed plate and vertically disposed spaced side plates thereon extending upwardly from opposite sides thereof, with means for adjusting the position of said plates to direct the heat reflected therefrom.

4. A heat reflector and draft excluder, comprising a horizontally disposed reflecting plate and a pair of substantially vertically disposed reflecting plates secured to and extending from opposite sides of said horizontal plate, respectively, opposite side supporting legs mounted on said vertically disposed plates at adjacent ends thereof, respectively, and the opposite end of said plates

adapted to be supported on a heating apparatus with the space between said plates substantially in line with the fire chamber of said heating apparatus and the said plates extending forwardly from the heating apparatus and supported at the forwardly extended end by said legs, the said legs vertically adjustable to raise and lower said heating plates, whereby the reflected heat may be directed upwardly or downwardly from the heating apparatus.

5. In a portable heat reflector and draft excluder, the combination with reflecting plates adapted to be detachably mounted on and extend exteriorly from a heating apparatus, of means for adjusting said plates to meet the requirements of various installations and said means permitting adjustment of said plates to vary the direction in which the heat is reflected and guided thereby and therefrom in operation.

Dated this nineteenth day of January, 1920.

CHARLES WRAY.
